United States Patent Office

Des. 218,847
Patented Sept. 29, 1970

218,847

DRYING FRAME

Mildred C. Specht, 704 S. Ward Ave.,
Compton, Calif. 90221

Filed Aug. 25, 1969, Ser. No. 18,832

Term of patent 7 years

Int. Cl. D7—06

U.S. Cl. D49—1

FIG. 1 is a perspective view of the front and one side of a drying frame showing my new design;

FIG. 2 is a side elevational view of said drying frame;
FIG. 3 is an end elevational view of the drying frame.

I claim:

The ornamental design for a drying frame, substantially as shown and described.
